DAMPED DRIVE-MECHANISM

Arthur M. Wahl, Wilkinsburg, Pa., assignor to
Westinghouse Electric Corporation, East Pittsburgh, Pa., a corporation of Pennsylvania

Application November 5, 1941, Serial No. 417,886

2 Claims. (Cl. 74—574)

My invention relates to a driver-and-load combination in which the driver or prime-mover, or the load, or both, are subject to torsional oscillations or hunting, superimposed upon the steady rotational movement of a shaft; and my invention particularly relates to a damping-means which is attached to the rotating part, preferably at a point approximating the point of maximum oscillatory movement, for damping such oscillations.

My invention, while of broad application in other situations, was especially designed for an induction-motor fan-drive in which a large centrifugal fan, having an inertia several times larger than that of the motor, was driven by an electric motor having a speed-torque curve of a type in which the torque increases with increasing speeds, over a certain speed-range at which the motor is intended to operate for material periods of time, so that, if the speed should momentarily increase, for any cause, the torque would also increase, tending to still further increase the speed, thus producing what is known as negative damping, resulting in oscillatory hunting or speed-variations above and below an average or steady-state speed. The particular motor which was used in the installation for which my invention was first developed was an efficient or low-slip 60-cycle motor having a low-resistance squirrel-cage winding, this motor being utilized to drive a heavy centrifugal fan through long shafting and speed-reduction gearing, and requiring an unusually long period of time to bring the load up to speed during the starting-period, because of the high inertia of the load, this starting-period lasting for a material period of time, which was from some 25 to 44 seconds, in different applications of the drive. Such induction-motors are well known to have a speed-torque characteristic in which the torque-speed curve is sharply inclined in the range from the vicinity of half-speed up to the pull-out point, which is fairly close to the synchronous speed, after which the torque falls off to zero at full synchronism, and the motor operates at a point at which the torque is perhaps one-third or one-half of the pull-out torque.

It was found that this drive-combination developed a serious vibratory oscillation, or low-frequency hunting, during the range of maximum negative damping, developing torsional pulsations at a rate of the order 3.8 cycles and 5.8 cycles, respectively, in two different installations. This hunting not only made the motor-drive mechanism noisy and set up considerable vibration, but it also imposed excessive torques on the couplings

and other vulnerable portions of the driving mechanism, and these excessive torques were believed to be considerably in excess of the safe fatigue-limits of the materials, so as to seriously endanger the life of the apparatus as a result of the probable failure thereof, due to fatigue, if this torsional vibration were not very materially reduced.

An object of my invention is to provide damper-means coupled to the motor-shaft, for developing an oscillating movement responsive to the oscillatory component of the motor-speed, and for damping such oscillating movement.

A more specific object of my invention is to provide a mechanically resonant damper-means having a natural frequency somewhere near the natural frequency of the motor-drive condition which is to be damped, so that a relatively slight and unimportant oscillatory component of the motor-speed will produce a relatively large oscillatory movement in the damper.

A still more specific object of my invention is to provide a damper utilizing a filling of a low-viscosity liquid, which is moved back and forth, as a result of the torsional oscillation, and is caused to flow through an orifice, in which damping is produced approximately in accordance with the square of the velocity of the liquid, and substantially independent of the viscosity, and hence the temperature, of the liquid.

With the foregoing and other objects in view, my invention consists in the parts, combinations, apparatus, and methods hereinafter described and claimed, and illustrated in the accompanying drawing, wherein:

Figure 1 is a somewhat diagrammatic view of a motor-drive combination in which my invention is utilized.

Fig. 2 is a transverse cross-sectional view 40 through my damper, and

Fig. 3 is a longitudinal sectional view thereof, on the broken plane indicated by the lines III—III in Fig. 2.

In Fig. 1, I have illustrated my invention as being applied to a motor-drive combination in which a heavy centrifugal fan 4, having a very considerable rotative inertia, is driven from a coupling 5 and a long shaft 6 having considerable torsional resilience, from a reduction-gearing 7 which is illustrated as a gear-wheel 8 which is carried by the shaft 6, and a pinion 9 which is carried by a drive-shaft 11. The drive-shaft 11 is driven, at any one of a plurality of speeds, by either a large high-speed motor M, which is coupled thereto at 12, or a small low-speed motor

M' , which is coupled thereto at 13, so that the drive-shaft 11 may be driven at a plurality of speeds. My invention particularly concerns the functioning of the large high-speed motor M , but the entire combination is shown, in order to show the precise installation for which my invention was primarily designed. The small motor M' , in one particular installation, was a two-speed motor, rated at $5\frac{1}{2}$ horsepower at 595 R. P. M., or at 0.9 horsepower at 290 R. P. M. The large motor M , in the same installation, was rated at 40 horsepower at 1170 R. P. M., this large motor M being an efficient six-pole, 60-cycle, squirrel-cage, induction-motor having a low-resistance squirrel-cage winding for causing the motor to operate at high efficiency and a low slip. This motor had the negative-damping torque-speed characteristic, as previously described, which was particularly evident at speeds in the vicinity of two-thirds of the full speed.

In the installation just described, the centrifugal fan 4 had a moment of inertia many times greater than that of the large motor M , so that any torsional oscillations which were set up as a result of the negative damping in the motor became apparent at the shaft 14 of the large motor M , rather than at the shaft 15 of the fan 4. In one such installation, the frequency of the hunting which developed during the starting period was of the order of 3.7 to 3.9 cycles per second, while in another installation of somewhat different size, the hunting-frequency was of the order of 5.7 to 5.9 cycles per second.

My present invention consists in the application, to the motor shaft 14 of a motor-driven combination such as that just described, of a small damper 16 which is coupled to the drive-connection which extends from the motor M to the fan or load 4, being connected to said drive-mechanism at a point close to the motor, or, in general, at a point close to the member having the smaller inertia. In the illustrated case, this means that the damper 16 is coupled to the motor-shaft 14.

As shown in detail in Figs. 2 and 3, my damper 16 comprises an annular housing 17, comprising an annular cup-shaped housing-member having an outer cylindrical wall 18, an inner cylindrical wall 19 which surrounds the motor-shaft 14, and which is keyed thereto at 21 (Fig. 2), and a radially extending annular disk-member 22 which joins the inner and outer cylindrical members 19 and 18 together in a rigid, unitary structure. The open side of the cup-shaped annular member is adapted to be closed by a removable annular disk-member 23 which is bolted thereto. Disposed within the annular housing 17 is a rotatably mounted weight-member 24 which is illustrated as having two cutaway portions 25 therein for providing a space 26 within the outer cylindrical wall 18 of the housing 17. In the center of each of the spaces 26, there is disposed a partition-member 27 which is screwed to the outer cylindrical wall 18 at 28 (Fig. 2), and which serves as an abutment for two springs 30 which resiliently center the weight-member 24 with respect to the partitions 27, while permitting the weight-member to have a certain yieldable oscillatory movement in response to the inertia-forces resulting from the oscillatory component of the rotating movement which is imparted thereto by the motor-shaft 14.

In the damper-member 16, the mass of the weight-member 24, and the resilience or spring-constant of the springs 30 are so chosen with

respect to each other that the damper-member has a natural frequency of the oscillatory weight-movement which corresponds approximately to the frequency of the most objectionable oscillatory shaft-movement components which are to be damped. In this manner, the amplitude of the arc through which the weight-member 24 oscillates is several times larger than the arc or amplitude of the oscillatory movement which is superimposed upon the steady rotational movement of the motor-shaft 14; and means are provided, in accordance with my invention, for interposing some sort of resistance to this relative amplified movement of the weight-member 24 with respect to the housing-member 17 of the damper 16. This movement-opposing resistance can be just plain friction, which would be fairly constant, or viscous oil-damping, which would vary approximately as the velocity of the relative movement of the weight-member with respect to the housing-member, but I believe that very much better results are obtainable with a movement-damping means which develops a movement-opposing force which is proportional to, or nearly proportional to, the square of the relative velocity of the weight-member 24 within the housing-member 17; and I find that a very desirable means for obtaining such a squared-velocity damping is by means of a filling of a light oil, or other low-viscosity liquid, which is shown within the spaces 26 within the annular housing-member 17. The partition-members 27 or the weight-member 24 or both, are provided with orifices 32, as shown in connection with the partition-members 27 in the illustrated embodiment of my damper.

If the viscosity of the damping liquid is low, such as is obtainable in a very light oil, the resistance to the movement of the liquid through the orifices 32 will be substantially proportional to the square of the velocity of such movement, and substantially unaffected by the viscosity, so that any changes in viscosity which are produced by temperature-changes in the oil will have practically no effect upon the damping, which is a very desirable feature. The arrangement is such that the relative oscillatory movement of the weight-member 24 within, and with respect to, the annular housing member 17, produces a back-and-forth movement of the oil causing the latter to flow back and forth through the orifices 32, thus damping such movement. At very low amplitudes of oscillation of the weight-member in the damper, the frictional damping, due to friction between the weight-member and the housing, and also that due to the viscosity of the oil, predominates over the velocity-squared damping due to the orifice. Of course, friction can be to a large extent reduced by using anti-friction bearings between the movable weight-member and the housing.

In the design of my damper, it is desirable that the orifice 32 be of sufficient size to permit the weight-member to have a considerable amplitude of oscillating movement, so that its movement will be considerably larger than the oscillating component of the rotary shaft-movement. This is so, because there can be no damping unless there is weight-movement, and it is desirable to make the damper so that a small oscillatory movement of the shaft will produce the amount of weight-movement necessary to produce positive damping to overcome the negative damping in the motor M .

In actual operation, I have found my damper-

means 16 to be so effective that a small damper, of 12 inches diameter, is sufficient to reduce the amplitude of the torsional oscillations of the shaft 14 to a very low amplitude (of the order of 3° to 6° at the motor shaft), a value which is negligible from a stress-standpoint, and which is quite unobjectionable from the standpoint of noise and vibration.

I claim as my invention:

1. A rotating-shaft means of a type having characteristics such as to tend to produce objectionally large torsional oscillations of a particular frequency-range, superimposed on a rotating-movement, over a particular speed-range at which the rotating-shaft means is intended to operate for material periods of time, and damper-means coupled to the shaft, said damper-means comprising an annular housing coupled to the shaft, oscillatably movable weight-means within said annular housing, spring-means for yieldably resisting relative movement between the weight-means and the housing, a filling of a low-viscosity liquid in said housing, and partition-means carried by the housing within said liquid, the weight-means being adapted to cause a movement of the liquid within said damper-housing as a result of the oscillatory movement of the weight-means relative to the housing, the partition-means being adapted to resist such movement of the liquid, and the system of weight-means and partition-means providing, in effect, orifice-means of such adequate dimensions as to permit orifice-restricted liquid-flow in sufficient amounts, in both directions, to permit a relatively large amount of oscillatory movement of the weight-means near the frequency-range of said torsional oscillations, the viscosity being so low and said orifice-means having such orifice-opening as to damp said oscillatory movement with a force which varies with the velocity of movement at a rate greater than the first power of said velocity under intended operating-conditions of the damper-means, said weight-means and spring-means having a natural frequency of resonance approximating the principal frequency of the torsional oscillations of the shaft.

5 2. Torsional oscillations to which the shaft is subjected, whereby the amount of angular movement of the weight-means relative to the damper-housing is greater than the amount of the superimposed angular oscillation which is transmitted from the shaft to the damper-housing.

10 2. Damper-means adapted to be mechanically coupled to a shaft subject to torsional oscillations superimposed on rotating-movement, said damper-means comprising an annular housing adapted to be coupled to the shaft, oscillatably movable weight-means within said annular housing, spring-means for yieldably resisting relative movement between the weight-means and the housing, a filling of a low-viscosity liquid in said housing, and partition-means carried by the housing within said liquid, the weight-means being adapted to cause a movement of the liquid within said damper-housing as a result of the oscillatory movement of the weight-means relative to the housing, the partition-means being adapted to resist such movement of the liquid, and the system of weight-means and partition-means providing, in effect, orifice-means of such adequate dimensions as to permit orifice-restricted liquid-flow in sufficient amounts, in both directions, to permit a relatively large amount of oscillatory movement of the weight-means under predetermined operating-conditions, the viscosity being so low and said orifice-means having such orifice-opening as to damp said oscillatory movement with a force which varies with the velocity of movement at a rate greater than the first power of said velocity under intended operating-conditions of the damper-means, said weight-means and spring-means having a natural frequency of resonance approximating the principal frequency of the torsional oscillations to which the shaft is subjected, whereby the amount of angular movement of the weight-means relative to the damper-housing is greater than the amount of the superimposed angular oscillation which is transmitted from the shaft to the damper-housing.
